UNITED STATES PATENT OFFICE.

ANNA C. GURSKE, OF OMAHA, NEBRASKA.

FILE-WRAPPER.

1,382,780.

Specification of Letters Patent. Patented June 28, 1921.

Application filed February 5, 1921. Serial No. 442,681.

To all whom it may concern:

Be it known that I, ANNA C. GURSKE, a citizen of the United States, residing at Omaha, in the county of Douglas and State 5 of Nebraska, have invented certain new and useful Improvements in File-Wrappers, of which the following is a specification.

This invention relates to a file wrapper of a type generally constructed of pasteboard, 10 having a flat form and open at its ends, and arranged to be opened and closed by bending its cover.

The invention has for its object, broadly, to provide a file wrapper which will be convenient in use and will consist of few and simple parts so that it will be durable and may be economically manufactured. The invention includes resilient members attached to the back and which extend over 15 one of the sides for normally moving a pressure-flap downwardly for retaining the contents of the file wrapper, and also the provision of a pressure flap having an upset flange serving as a finger-piece for its control, and also providing a guide, convenient 20 in operation, when inserting the contents to be held by said flap. The invention also includes convenient means for connecting the metallic, resilient members to the back of the 25 wrapper.

With the foregoing objects in view the invention presents a novel construction, combination and arrangement of parts, as described herein and claimed, and as illustrated 30 in the accompanying drawing, wherein,—

Figure 1 is a top plan view of the file wrapper, partly in section. Fig. 2 is a bottom plan view of the same. Fig. 3 is a transverse section on line 3—3 of Fig. 1, the scale 40 being enlarged. Fig. 4 is a similar view to that shown in Fig. 3, the cover-leaf being released from the pressure-flap. Fig. 5 is a top plan view showing a pressure-flap and a part of the back. Fig. 6 is a bottom plan view 45 showing a housing-strip and a part of the back.

Referring now to the drawing for a more particular description, the file wrapper consists, in part, of a flexible sheet preferably 50 constructed of pasteboard, having a part bent, as indicated at 7 to provide a back 8 and a cover-leaf 9, and having a second part bent, as indicated at 10, to provide a pressure-flap 11 adapted to overhang a part of 55 the back, said flap 11 being provided with a flange 12 adjacent to its longitudinal edge

operative as a guide and useful as a lifting-member.

In order that paper sheets or other contents 13 may be held, and will not slide outwardly of the open ends of the wrapper, and that the outer end portion of the leaf 9 may be held in closed position, I provide resilient members 14, preferably constructed of pieces of wire, each being bent at its middle, as indicated at *a* to provide a pair of arms having portions *b* extending divergently from the part *a* adapted to constantly engage the flap 11, and bent at its ends to provide a pair of loops or hooks 15 adapted to engage the back 70 8, said arms being bent to a curved form, as indicated at *c*, between said loops and divergent portions *b* to be disposed adjacent to the bent portion 10 of the flexible sheet.

As thus described the parts of each member 14 which are disposed upon the flap 11 are approximately of V-shape and the degree of resiliency of said members 14 is such that said V-shaped portions will be pressed against the flap 11 with considerable force so 80 that the sheets or contents 13 will be securely held between said flap and the back 8.

In order that the loops 15 will be maintained in engagement with the back 8 I provide a housing-strip 16 and base-strip 17, 85 each being traversed by the arms of the resilient members 14, the base-strip completely covering the loops 15, and the housing-strip covering the base-strip, suitable adhesive material being used for connecting 90 the housing-strip to the base-strip and for securing said members to the back 8.

When the parts are disposed as shown in Fig. 3, the cover 9 and sheets 13 will be securely held by the resiliency of members 14. 95 To open the file wrapper, the leaf or cover 9 may be readily bent upwardly for removing it from beneath the flap 11, and when said leaf has been swung to open position, the flap 11, by action of members 14 will be 100 pressed downwardly upon the sheets 13, and one or all of the sheets may be removed from the file wrapper against the force of members 14, the flange 12 being used, when required, for manually lifting the flap 11.

When placing the sheets 13 within the file wrapper, they may have a sliding movement beneath the flap 11 toward the bent part 10. Another function discharged by the flange 12, in addition to its use as a tab or lifting-member, is that it operates as a buffer for the projecting parts *a* and prevents the lat-

ter from operating as obstructions to the movement of the paper sheets or cover 9 when inserting them beneath the flap 11.

While I have shown two resilient members 5 14, it will be understood that the number thereof may be changed, and while I have shown and described construction in detail, I do not wish to be understood as limiting myself in this respect, and changes 10 in size, form, proportion and minor details may be made, as found to be of advantage, said changes to be determined by the scope of the invention as claimed.

I claim:

15 1. A file wrapper, consisting of a flexible sheet having a bent portion providing a back and a cover and having a second bent portion providing a flap above the back, resilient, metallic strands for pressing the 20 flap toward the back, each strand being bent midway between its ends to approximately V-shape to provide divergent parts adapted to lie upon the flap and providing curved parts adapted to be disposed adjacent to the second bent portion of the flexible sheet, and providing loops for engaging 25 said back, a base-strip on the back disposed on said loops, and a housing strip engaging the back and base-strip, the flap of said flexible sheet being bent upwardly to provide 30 a lifting-member.

2. In a file wrapper, the combination with a flexible sheet having a bent portion providing a back and a cover and having a 35 second bent portion providing a flap above the back, of a resilient, metallic strand for pressing the flap toward the back, said strand being bent midway between its ends to approximately V-shape to provide parts 40 adapted to lie upon the flap and providing curved parts adapted to be disposed adjacent to the second bent portion of the flexible strip, and providing loops for engaging said back, a base strip on the back 45 engaging said loops, and a housing strip engaging said back and base-strip.

3. In a file wrapper, the combination with a rectangular, flexible sheet having a bent

portion providing a back and a cover and having a second bent portion providing a 50 flap above the back, of a pair of bent, resilient, metallic strands, each having a part disposed upon the flap for pressing it toward the back and having a pair of loops engaging said back, and a housing-strip 55 traversed by said strands, said housing-strip being disposed outwardly of the loops and secured to the back.

4. In a file wrapper, the combination with a flexible sheet having a bent portion providing a back and a cover and having a second bent portion providing a flap above the back, of a plurality of bent, resilient, metallic strands, each having a part disposed upon the flap for pressing it toward the back and having a pair of loops engaging the back, a housing-strip secured to the back and traversed by the strands to permit the loops to be disposed between the back and said housing-strip, the flap of said flexible sheet being bent upwardly to provide a terminal flange extending its entire length.

5. A file wrapper, consisting of a rectangular, flexible sheet having a bent portion to provide a back and a cover and having a second bent portion providing a flap above the back, a plurality of resilient, metallic strands for pressing the flap toward the back, each strand being bent midway 75 between its ends to provide divergently disposed parts adapted to lie upon the flap and providing loops for engaging the back, a housing-strip secured to the back and traversed by the strands and disposed outwardly of said loops, the flap of said flexible sheet being bent transversely throughout its entire length to provide a terminal flange.

In testimony whereof I have affixed my 90 signature in presence of two witnesses.

ANNA C. GURSKE.
